UNITED STATES PATENT OFFICE.

CARL HEINRICH MAX DÖRNTE, OF HAMBURG, GERMANY.

TACKLE BLOCK.

Application filed July 20, 1920. Serial No. 397,804.

(GRANTED UNDER THE PROVISIONS OF THE ACT OF MARCH 3, 1921, 41 STAT. L., 1313.)

To all whom it may concern:

Be it known that I, CARL HEINRICH MAX DÖRNTE, citizen of the German Republic, residing at No. 11 Brauerknechtsgraben, 5 Hamburg, Germany, have invented new and useful Improvements in Tackle Blocks (for which I have filed applications in Germany February 2, 1914, patented March 10, 1921, Number 334139, and Great Britain February 10, 1914, patented July 23, 1914, Number 3823), of which the following is a specification.

This invention relates to tackle blocks and in particular to tackle blocks having multiple sheaves and being principally designed for use in lowering life boats. It is the object of my invention to provide a tackle block of an improved structure, in which the rope lines pass through individual guides 15 provided above each sheave, said guides thus effectively prevent tilting of the block. A further object of my invention is to provide an improved form of guide. A still further object of my invention is to provide for said guides a carrying member of an improved structure. A still further object of my invention is to provide for simply and effectively securing said guide bars within the casing of the block. A still further object 20 of my invention is to mount said guide carrying member intermediate the side plates of each sheave, and to secure the same by the same means by which the plates are fastened to each other, my novel rope line guiding means being especially adapted to be attached to and employed in conjunction with ordinary old tackle blocks whether the same be made of wood or iron.

With these and other objects in view I 25 have illustrated some practical embodiments of my invention, by way of example, in the accompanying drawings, it being understood that the same, or parts thereof, are susceptible to modifications such as will readily suggest themselves to those skilled in the art to which this invention appertains, without thereby involving a departure from the scope of my invention. In the drawings Fig. 1 is a front elevation of a tackle block, 30 furnished with my invention, Fig. 2 showing a side view, and Fig. 3 a plan view of the same. In Fig. 4 I have illustrated, in front elevation, a wooden block equipped

with my invention, while Fig. 5 is a side view, and Fig. 6 a top view of the same. 55

Referring to the drawings the sheaves *a*, which may be provided with suitable bearings, such as roller bearings, are revolvably mounted on a transverse pin *b* which passes through the covering plates *c* and both parallel extending legs of each of the stirrups *d* and *e*; the covering plates *c* being secured to the legs of the outer stirrup *d*. The covering plates *c* on either side are interconnected by means of screw threaded 60 bolts *f* which also pass through intermediate plates *g* provided on either side of the legs of the inner stirrup *e*. The bolts *f* pass through, and support, distancing pieces or sockets *h* extending between each two adjacent plates *c*, *c*, and *g*, *g*. The bolts *f* in the top part of the block support the bars *h'* which in the illustrated embodiment of my invention occupy the place of the outer pair of sockets *h* only the median sockets *h* 65 being employed still for distancing the plates *g* relatively to each other. These median sockets *h* on the upper transverse bolts, too, may be dispensed with in favour of a third bar *h'* placed there instead, so that then, a 70 bar *h'* is provided over each sheave employed in the block. Each bar *h'* is provided with a passage *i* for a rope line, the rope being thereby effectively guided and thus prevents the discharge block from tilting and getting into disorder. The said 75 passage *i* may consist of a hole bored through the bar *h'*. I prefer to line the passages *i* by means of special guide pieces or sockets *k* which may be made of wood, 80 lignum vitæ, fibre, or the like. The sockets *k* are preferably provided with a circumferential contraction into which the respective bar *h'* enters for the purpose of fixedly holding the sockets. I prefer to compose 85 each bar *h'* of halves clamped together between the walls of the block by means of the above mentioned bolts *f*, the plane of section extending lengthwise of the bar. Both ends of each bar *h'* are suitably curved 90 to embrace the respective socket *k* by entering into the contracted portion of the socket which is thus secured in place through the clamping action of the bolts *f*. No further fastening means are required for the sockets *k*. 95 100 105

The central passage of each socket *h* is of such a form and finish as to prevent any damage to the rope line passing therethrough.

5 The wooden tackle block shown in Figures 4 to 6, is of a similar construction and assembled in the same manner as the tackle block hereinbefore described; except that the inner stirrup is duplicated for apparent 10 reasons. The sockets *h* as well as the rope guiding bars *h'* are similar to those described in connection with the iron tackle block illustrated in Figures 1 to 3. I prefer to give the sockets *h* a cylindrical form and 15 to provide ample space between two parallel disposed sockets in order to prevent water and moisture from accumulating in contact therewith, and to provide for an unobstructed access of air. Making the median 20 sockets *h* of fibre secures the advantage that the sockets will not be liable to shrink or otherwise alter its form in consequence of alteration in the atmosphere.

If it is desired to equip an old tackle 25 block with my novel rope guiding bars, this may be accomplished by removing the distancing sockets at the top of the block and substituting the rope guiding bars *h'* therefor, which may be secured in place by means 30 of the old screw threaded bolts or rivets.

Safety blocks hitherto known having a 35 guide plate above the middle sheave, require the provision of special fastening means for the guide plate which is not adapted to allow of being readily attached to old tackle blocks.

In the illustrated block constructions, the eye for the swivel which engages the hook that is to be connected to the life boat, is formed by the curved portions of the stirrup *d* and *e*.

What I claim as my invention and desire to secure by Letters Patent of the United States of America, is:—

40 1. A tackle block, comprising in combination, at least one revoluble sheave, side plates for said sheave, a member above said sheave and composed of lengthwise extending

halves, said member being mounted between said side plates, apertured structures one at each end of said bar and adapted to receive 50 and guide a rope line of said sheave, said structures being secured in place between said halves of said member.

2. A tackle block, comprising, in combination, at least one revoluble sheave, side 55 plates on either side of said sheave, transversely extending fastening means for said side plates, a member disposed above said sheave and consisting of lengthwise extending halves, said member being mounted between said side plates and secured in place by means of said fastening means, apertured structures one at each end of said member and adapted to receive and guide a 60 rope line of said sheave, said structures being held in place between said halves of said member.

3. A tackle block, comprising, in combination, a plurality of revoluble sheaves, side plates on either side of said sheaves, transversely extending fastening means for said side plates, individual members above at least two of said sheaves, each member consisting of lengthwise extending halves, said 70 halves being mounted between the said side 75 plates of the associated sheave and by means of said fastening means, apertured structures one for each end of each of said members and adapted to receive and guide a rope line of the associated sheave, and a contraction on each of said structures and adapted to receive the respective ends of the associated member, whereby said structures are held in place through said fastening means acting upon said halves of said 80 members.

In testimony whereof I have signed my name to this specification in the presence of two subscribing witnesses.

CARL HEINRICH MAX DÖRNTE.
